DESIGN FOR A COAT

Philip Rosenshein, New York, N. Y.

Application May 13, 1941, Serial No. 100,915

Term of patent 3½ years

To all whom it may concern:

Be it known that I, Philip Rosenshein, a citizen of the United States, residing in New York city, in the county of Kings and State of New York, have invented a new, original, and ornamental Design for Coats, of which the following is a specification, reference being had to the accompanying drawing, forming part thereof, in which—

I claim:

The ornamental design for a coat, as shown.

PHILIP ROSENSHEIN.
